UNITED STATES PATENT OFFICE.

WILLIAM GOODFELLOW, OF OAKLAND, CALIFORNIA.

INTERNAL-COMBUSTION ENGINE.

Application filed April 13, 1922. Serial No. 552,374.

The present invention relates to improvements in internal combustion engines and its particular object is to provide means in connection with the commonly used internal combustion engine having a charge forming device for admitting fuel into the combustion chamber in a gaseous state for introducing liquid containing explosive material into the gaseous charge whereby the effectiveness 5 of the combustion is increased. A further object of the invention is to provide suitable means for controlling the supply of liquid into the charge. A further object is to cause these control means to be governed by 10 the exhaust gases of the engine in such a manner that when the engine is running slowly very little or no liquid is introduced while as the engine speeds up the liquid supply is increased. A further object is to 15 provide suitable means preventing the liquid from flooding the charge forming device, the latter means being adapted at the same time to admit a desired amount of air into the liquid.

With these objects in view I have illustrated the preferred form of my invention in the accompanying drawing in which Figure 1 shows a side elevation of an internal combustion engine such as might be used in 20 a motor vehicle with my device attached thereto; Figure 2 is a sectional detail view of a valve operating mechanism along line 2-2 of Figure 1 and Figure 3 a sectional detail view of another valve taken along 25 line 3-3 of Figure 1. While I have illustrated only the preferred form of my invention I wish to have it understood that various changes or modifications may be made 30 within the scope of the claims hereto attached without departing from the spirit 35 of the invention.

The engine (1) shown in the drawing is 40 of the ordinary type used for motor vehicles and is provided with a carburetor (2), an intake manifold (3) and an exhaust manifold (4). A communicating pipe (6) connects the carburetor with the intake manifold and the throttle (7) is shown adjacent 45 the carburetor. The latter receives its fuel such as gasoline from any suitable source 50 not shown in the drawing, through the pipe (8). These details are well known in the art and the operation of this device is well understood. The current of air is sucked 55 past the gasoline in the carburetor by the intake strokes of the various pistons and

carries gasoline vapor with it to form a proper charge for the combustion chamber. The amount of charge admitted is regulated 60 by the throttle (7).

The object of the present invention is to introduce an additional element into the explosive mixture which will increase the power of the explosion. This additional element is in liquid form and may consist of a 65 solution of saltpeter, water and sulphur. Ideal results have been obtained with the mixture made up of one part of saltpeter, two parts of water and three parts of sulphur.

This liquid I store in the tank (9) which 70 may be placed underneath the front seat or in any other suitable position. A tube (11) leads from this tank to the communication 75 (6) between the intake and the carburetor preferably underneath the throttle (7) so that the supply of liquid will be subject to the throttle control in the same manner as the gasoline charge coming from the carburetor.

I have found from actual experience 80 that the addition of this liquid to the gasoline charge is most desirable when the engine is running at full speed and least desirable when the engine is running slowly. I have therefore developed a means which is 85 automatically controlled by the speed of the engine for controlling the liquid supply in the desired manner. This means is illustrated in detail in Figure 2 and comprises a valve (12) within the tube (11) and a control 90 for this valve actuated by the exhaust gases of the engine. The valve (12) is conical shaped and fits in a conical seat, a perforation (13) in the valve being adapted to 95 register with the tube (11) in a certain position while closing said tube when turned through a quarter of a turn. The vertical 100 valve stem (14) extends to within close proximity of the exhaust pipe (17) and is rotatably supported in the housing (16) covering a portion of the exhaust pipe, the latter being provided with an opening (18) 105 allowing the vane (19) rigidly secured to the vertical stem (14) to extend into the exhaust pipe so as to be struck by the exhaust gases. Normally the valve (12) is in 110 a position where it closes the tube. The exhaust gases in striking the vane (19) tend to turn the valve stem into a position where the perforation (13) registers with the tube (11) thereby opening the same. The tendency of the exhaust gases to open the valve

110

is counteracted by suitable springs (21) tending to close the valve. In this manner the exhaust gases and the springs will co-operate in causing the vane (19) to oscillate, 5 opening the valve for brief intervals when the oscillations are sufficiently strong to cause the perforation in the valve to register with the tube. This is the case only when the machine is running at full speed 10 or almost at full speed so that my liquid fuel is admitted into the charge only at that time and then in very small quantities. To convey an idea as to the quantity of liquid to be used I might state that I ordinarily use 15 about one and one-half pint of solution to a gallon of gasoline, without of course wishing to limit myself to that amount.

In Figure 3 will be noticed a detail view 20 of a second valve (22) provided in the tube (11). This valve serves various purposes. A ball (23) is confined in an angular recess (24) of a downwardly extending passage (26). Normally this valve will allow any 25 liquid to pass through the same so as to prevent it from passing into the carburetor due to the bouncing of the ball on its seat through the effect of engine suction at slow speeds and vibration of the automobile. But when the running engine creates sufficient 30 suction in the pipe (11) to draw the ball (23) toward the upper seat (27) the opening (26) will be closed and liquid will pass the same. It is understood, of course, that this suction is pulsating and does not 35 hold the ball against its seat continuously but allows the same to vibrate and allows air to pass through the valve during these vibrations, which air will be mixed with the passing liquid. This valve therefore acts 40 in a similar manner as the valve (12) and allows liquid to pass only when the engine is running sufficiently fast to create a suction strong enough to hold the ball against its seat.

45 It will be noted from the foregoing description that the liquid containing the explosive is thus allowed to enter the communicating pipe (6) together with the gasoline charge from the carburetor and is 50 drawn into the engine by the suction of the

same, rendering the explosion of combustion more powerful. Suitable means are provided for regulating the supply of this liquid in the two valves both of which are governed by the speed of the engine since 55 more speed, of course, means more intense suction and more intense exhaust.

I claim:

1. An internal combustion motor having an intake pipe and an exhaust pipe provided with a lateral opening, an auxiliary fuel supply tank, a tube connecting the fuel supply tank with the intake pipe, a turnable valve within the tube for controlling the flow of fuel from the auxiliary fuel supply 60 tank to the intake pipe, a valve stem extending outwardly from the valve, tensionable means connected to the valve stem for yieldingly holding the valve in closed position, and a vane extending laterally from 65 the valve through the opening of the exhaust pipe and into the path of movement of the exhaust gases and operable thereby to open the valve against the action of the tensionable means. 75

2. An internal combustion motor having an intake pipe and an exhaust pipe provided with a lateral opening, an auxiliary fuel supply tank, a tube connecting the auxiliary fuel supply tank with the intake pipe and 80 having an outwardly and downwardly extending air passage, a gravity operated valve normally closing the said air passage and responsive to the suction within the intake pipe to open the air passage whereby 85 air is admitted into the tube, a turnable valve within the tube for controlling the flow of fuel from the auxiliary fuel supply tank to the intake pipe, a valve stem extending outwardly from the valve, tensionable 90 means connected to the valve stem for yieldingly holding the valve in closed position, and a vane extending laterally from the valve through the opening of the exhaust pipe and into the path of movement of the 95 exhaust gases and operable thereby to open the valve against the action of the turnable means.

WILLIAM GOODFELLOW.
